MICROWAVE ELECTRONIC AMPLIFIER

Ernest G. Linder, Philadelphia, Pa., assignor to
Radio Corporation of America, a corporation
of Delaware

Application July 25, 1936, Serial No. 92,561

8 Claims. (Cl. 179—171)

This invention relates to micro-wave amplifiers. More specifically, it relates to improved magnetrons or electronic discharge devices which are provided with means for obtaining an operating characteristic and means suitable for amplifying ultra high frequency currents.

Numerous limitations in present day triode and pentode thermionic amplifying tubes render these tubes practically useless as amplifiers of micro-waves. For example, in a conventional triode, a very small input capacitance will act as a substantial short circuit at frequencies of the order of several thousand megacycles. If magnetrons or positive grid tubes are used, the capacity of the electrodes may be minimized and made part of the resonant circuit. I have devised improved means and adjustments for operating the latter types of tubes as micro-wave amplifiers.

One of the objects of my invention is to provide an improved method of and means for operating a magnetron as an amplifier of ultra high frequency currents. Another object is to provide an improved method of and means for operating a positive grid electronic discharge tube as a microwave amplifier.

My invention may be best understood by referring to the accompanying drawing in which

Fig. 1 is a schematic diagram of magnetron embodying my invention,

Fig. 2 is a schematic diagram of an embodiment of my invention applied to a positive grid tube, and

Figs. 3 and 4 are graphs illustrating one mode of operation of the circuit shown in Fig. 1.

Referring to Fig. 1 a magnetron 1 is composed of an evacuated envelope 3 within which are suitably mounted a cathode 5, a pair of split anodes 7 and a pair of end plates 9. A magnetic field is created by a solenoid 11, or the like, which surrounds the envelope 3. The solenoid may be energized by a battery 13. The anodes 7 are connected to a transmission line 15. The transmission line 15 terminates in a dipole antenna 17 which may be moved along the transmission line

to resonate or tune the line. The anode power supply 19 is connected between the cathode 7 and the midpoint of the dipole 17 through the radio frequency choke coil 21. The end plates 9 are made positive by a connection to a source of potential such as the anode power supply.

While the end plates are not essential, I prefer to use them as they aid in making adjustments of the tube characteristics. The cathode 5 is energized by any suitable power source 23. The output of the amplifier is represented by the loop

25 which is coupled to the transmission line and terminated in a detector, or the like, not shown.

Having described the circuit, I shall briefly describe the operation and method of adjusting the tube operating characteristics. Electrons emitted from the cathode 7, if no magnetic field be applied, travel in straight lines to the anodes. As a magnetic field, whose lines of force are substantially parallel to and surround the cathode, is applied, the path of the electrons becomes 10 curved. As the density of the magnetic field increases, radius of curvature of the electron path decreases. The magnetic field density may be made sufficient to return all the electrons to the cathode; i. e., cut off the anode current. 15

The various curvatures, effected by the magnetic field, establish different electron transit times, which may be related to the oscillatory frequency or wave length. This relation between wave length, and magnetic field is as follows:

$$\lambda = \frac{12000}{H}$$

where λ =wave length in centimeters, and H =magnetic field in gauss. The applied field 25 may also be related to the anode potential and anode radius as follows:

$$H = \frac{6.7V^{\frac{1}{2}}}{r}$$

where H =field in gauss, V =anode potential in 30 volts, and r =anode radius in centimeters.

The frequency or wave length of the amplifier is adjusted to the transmitter wave-length by resonating the transmission line. The next step is to adjust the magnetic field, in accordance with 35

$$\lambda = \frac{12000}{H}$$

so that the electron transit time will be substantially equal to the period of the transmitted wave. 40 The anode potential may now be adjusted until the electrons just graze the anodes, i. e., to just establish a small anode current. The anode current may be adjusted by varying the electron emission or by suitably adjusting the end plate 45 current. Assuming no incoming waves are being received, the characteristic may be represented by curve A of Fig. 3. This curve was obtained by plotting the relative radio frequency output against various values of D. C. anode current. 50 For example, the output power was measured in loop 25, although current or voltage measurements would be satisfactory. It will be observed that the radio frequency output is substantially zero until the anode current reaches .16 milliam- 55

- pere and the tube begins to oscillate. Above .16 milliampere the output current and the anode current both increase and the device is generating oscillatory currents.
- 5 If the transmitted waves are impressed on the resonant transmission line, the output will change from the characteristic A to B. Curve B is obtained by adjusting the tube to a given value of anode current when no signal is present, and 10 measuring the radio frequency output when a signal is impressed on the antenna. For low values of anode current, the received currents trigger the receiver into an oscillatory state. For high values of anode current, the oscillatory output 15 is shifted by the incoming signal as shown. The difference between the curves A and B is plotted in Fig. 4. The curve C of this figure represents the relative change in the radio frequency output caused by the application of the signal. It will be 20 observed that a maximum positive increase D, or a maximum negative decrease E may be obtained by regulating the anode current to .18 or .21 milliampere, respectively, by varying the cathode emission, end plate current or both.
- 25 The relative increase or decrease in output is a measure of the gain of the amplifier. Amplification of the carrier frequency of the incoming signal takes place at any point on curve C which is above the zero ordinate of output. Thus, when 30 the tube draws an anode current corresponding to a point on the curve above the zero ordinate, and when a modulated carrier frequency is impressed on the tube, an amplified modulated carrier of like frequency will appear at the output.
- 35 When the tube is operated with an anode current corresponding to a point on the curve below the zero ordinate, a signal tends to decrease the output. In this case, the amplification of the signal carrier is less than unity. But changes in 40 carrier amplitude, produced by modulation for example, give rise to amplified changes in the output. That is, the effective percent modulation of the output signal has been increased, even though the maximum carrier intensity has been 45 decreased. In either case, changes in the amplitude of the incoming signal result in changes in the output of the amplifier whose direction and degree is indicated by curve C.
- The maximum amplification of the carrier amplitude is obtained at point D on curve C. The 50 maximum resultant change in output produced by changes in the amplitude of an input signal is obtained at point E. The frequency of the output current substantially equals the incoming carrier frequency. The amplified currents are impressed on the resonant output circuit which is coupled to the transmission line.
- The circuit arrangement shown in Fig. 2 is 55 similar to Fig. 1 but differs from the latter by 60 the substitution of a positive grid electron tube for the magnetron. In Fig. 2 a positive grid tube is represented by reference numeral 27. The tube is composed of an evacuated envelope within which are concentrically mounted a cathode 29, grid 31, and split cylindrical anodes 33. The cathode 29 is heated by a battery 35. The grid 31 is biased positively with respect to the cathode by a battery 37. The anodes 33 may be biased slightly positive or negative by a battery 39 which 65 is connected from the cathode 31 through a radio frequency choke coil 41 to the midpoint of a dipole antenna 43. The dipole 43 is adjustably connected to a transmission line 45 which is 70 terminated in the split anodes 33. The work 75 or output circuit is composed of a loop 47 which

is coupled to the transmission line 45. The output circuit may include additional amplifiers, or a detector.

The operation of a positive grid electron tube is essentially as follows: The electrons move along 5 radial lines from the cathode through the grid to or toward the anode. Some of the electrons are then repelled by the anode and move toward the grid. Under the controlling electrical forces of a tuned circuit a cloud of electrons oscillate 10 back and forth between anode and grid. The transit period of the electrons may be adjusted to substantially the period of the tuned transmission line which connects the anodes. The operating characteristics of the positive grid tube 15 may be adjusted to give a characteristic similar to the magnetron operation illustrated by Figs. 3 and 4.

The precise theory of operation of the electronic amplifiers is not entirely understood but it is believed that both the magnetron and positive grid amplifiers operate substantially as follows: The electrons, traveling their cyclic paths, are timed so that their transit periods substantially equal the frequency of the incoming carriers. The incoming carrier currents are resonated by the tuned transmission line. The effect of the resonated incoming signal currents is to substantially increase the movement of the electrons. The increased electron movement is accompanied 30 by changing space charge conditions and changing anode current. The resulting changes, affect the output to thereby produce amplified currents which may be transferred to the output or work circuit.

35 I claim as my invention:

1. A microwave amplifier comprising in combination a magnetron amplifier having cathode and anode electrodes, a tunable circuit connected to said electrodes, means for impressing a magnetic field on said magnetron, means for impressing incoming carrier currents on said tunable circuit, and an output circuit coupled to said tunable circuit at a point of R. F. potential, whereby amplified currents substantially of the frequency 45 of said carrier currents are available at said output circuit.

2. A microwave electronic amplifier comprising in combination an electron discharge tube having cathode and anode electrodes, a resonant transmission line connected to said electrodes, means for impressing incoming carrier currents on said transmission line, an output circuit substantially resonant to the frequency of said carrier currents coupled to a point of radio frequency potential on said transmission line, and means for adjusting the operating characteristics of said tube so that said incoming carrier currents effect increased output currents substantially of the frequency of said carrier currents in said output circuit.

3. A microwave electronic amplifier comprising in combination a magnetron tube having cathode and anode electrodes, a resonant transmission line connected to said electrodes, means for creating a magnetic field for said magnetron, means for impressing incoming carrier currents on said transmission line, an output circuit coupled to a point of radio frequency potential on said transmission line, and means for adjusting the operating characteristics of said tube so that variations in said incoming carrier currents effect increased variations in the output currents in said output circuit, said output currents having 75

- substantially the same frequency as said incoming carrier currents.
4. A microwave electronic amplifier comprising in combination a magnetron tube having cathode, end plates and anode electrodes, a resonant transmission line connected to said electrodes, means for creating a magnetic field for said magnetron, means for impressing incoming carrier currents on said transmission line, an output circuit coupled to said transmission line, and means including said end plates for adjusting the operating characteristics of said tube so that said incoming carrier currents effect increased output currents in said output circuit.
5. A microwave electronic amplifier comprising in combination a positive grid electronic tube having cathode, grid and anode electrodes, a resonant transmission line connected to said anode electrodes, means for impressing incoming carrier currents on said transmission line, an output circuit coupled to a point of radio frequency potential on said transmission line, and means including said positive grid for adjusting the operating characteristics of said tube so that said changes in said incoming carrier currents effect increased changes in said output currents in said output circuit.
6. The method of amplifying microwaves by means of a magnetron tube which comprises applying a magnetic field to said magnetron so that the electron transit time substantially equals the period of said microwaves, resonating said microwave currents, impressing said resonated currents on said magnetron tube, obtaining output currents having a frequency substantially equal

to that of said microwave currents, and adjusting the anode current in said magnetron tube so that the amplified changes in said output currents are effected by changes in said resonated currents.

7. The method of amplifying microwaves by means of a magnetron tube having cathode, end plate and anode electrodes which comprises applying a magnetic field to said magnetron so that the electron transit time substantially equals the period of said microwaves, resonating said microwave currents, impressing said resonated currents on said magnetron tube, and adjusting the end plate current in said magnetron tube so that the output currents in said tube whose frequency is substantially equal to that of said microwave currents are substantially increased by the application of said resonated currents.

8. A microwave electronic amplifier comprising in combination an electron discharge tube having cathode and anode electrodes, a resonant transmission line connected to said electrodes, means for impressing incoming carrier currents on said transmission line, an output circuit substantially resonant to the frequency of said carrier currents coupled to a point of radio frequency potential on said transmission line, and means for adjusting the operating characteristics of said tube so that variations in the amplitude of said carrier currents effect increased variations in the amplitude of the output currents in said output circuit, said output currents having substantially the same frequency as said carrier currents.
